JOHN SPEIGHT, OF BRADFORD, ENGLAND.

Letters Patent No. 87,377, dated March 2, 1869.

IMPROVEMENT IN SPINNING-MACHINE.

The Schedule referred to in these Letters Patent and making part of the same.

To all whom it may concern:

Be it known that I, JOHN SPEIGHT, of Bradford, in the county of York, and Kingdom of England, have invented new and useful "Improvements in Machinery or Apparatus for Spinning, Twisting, and Roving Worsted, or other Fibrous Substances, to facilitate the doffing;" and I do hereby declare that the following is a full and exact description thereof, reference being had to the accompanying drawings, and to the letters of reference marked thereon; that is to say—

This invention relates to that class of machinery or apparatus for spinning, twisting, or roving, known as throste-frames and cap-frames; and

My improvements consist in the employment of duplicate spindles or bobbin-studs, that is, in having two sets of spindles or studs, so arranged, that while one set is in position for spinning, twisting, and roving, the other set is in position for doffing.

Each set, according to one method, is mounted on a shaft capable of turning on its axis, and also of sliding endwise, such shafts being placed and operated so as that each set of spindles or studs may change positions alternately, or as and when required; or other methods may be adopted of applying duplicate spindles or studs.

In carrying out this invention, I either employ fliers, suspended, by their necks, to a rail, over the spindles or studs, in which they are capable of rotating; or I use whorles or whirls, constructed so as to be capable of rotating in bearings formed in the lifter-rails, and traversed up and down thereby.

A guide-eye is fixed in each whorle or whirl, and a central hole is formed therein, of sufficient diameter to allow the bobbin, when filled with the spun or twisted yarn, to pass through it.

When employing fliers, I form a cup or cavity over or in each flier-neck, to fit a suspending boss or socket attached to the rail, and to contain oil or other lubricant.

In order that this invention may be clearly understood, I herein give reference to an accompanying sheet of drawings of an ordinary worsted-spinning frame, with my improvements applied thereto.

Description of the Drawings.

Figure 1 is a front elevation, and

Figure 2 is an end elevation of the same.

In these drawings, I have the application of fliers specially constructed for carrying out this invention.

These fliers, marked C, are suspended, by their necks, to a rail, D, fixed to the ordinary top rail of the frame E.

One set or series of the spindles or bobbin-studs F is fixed on a shaft, F', which is mounted in brackets F'', attached to the ordinary lifter-rail G.

Another set or series of spindles or bobbin-studs, H, is, in like manner, fixed to another shaft, H', which is also mounted in the said brackets F''.

These shafts are geared together by spur-wheels, I, and are coupled by a double collar or link, I'.

A lever-handle, J, is fixed on the shaft F', which passes through an oblique slot-hole in a plate, K, fixed to the frame.

The set of studs F is shown with the tubes a, and spools therein, and in proper position for the spinning-process, and for the yarn to be wound upon them, by the fliers, in the usual manner, while the other set, H, is shown without the bobbins, and placed out of position for the spinning-process, but in a suitable position to have the full bobbins doffed or removed therefrom, and empty bobbins placed thereon, ready for the spinning and winding the spun yarn upon them.

It will be readily seen that, if the lever-handle J be pressed downward, it will move in the slot, and thereby turn both the shafts F' and H' in opposite directions to each other, and also move them endwise, so that the two sets of studs will change positions or places, or that the studs F will be removed, for spinning and winding the spun yarn on the bobbins, but into position for doffing, and that, simultaneously therewith, the studs H will be placed in position for spinning and winding the spun yarn on the bobbins.

Rotary motion is communicated to the fliers from an ordinary roller, L, by straps or bands, L', acting on pulleys or whirls, L'', fixed or formed on the fliers.

The tubes a, on which the spools or bobbins b are placed, have rotary motion given to them by frictional contact with a strap, M, which is mounted on pulleys fixed on upright shafts, M' and M'', the former of which shafts being driven by a belt from a roller, N.

Figure 3 is a full-sized sectional view of the flier, and the rail in which it is suspended and rotates, showing its peculiar construction, and the method of suspension, and the provision made for the lubrication thereof; and also the bobbin-studs and their shafts, one of said studs having a spool-bobbin thereon, in proper form.

In this figure, c represents the tube of the flier, having a cup or cavity, d, to receive the boss or socket e, which is suspended from or attached to the rail.

The whirl f is screwed or secured to this cup, and serves to hold the flier, so that it and the whirl may both be sustained by and yet be free to rotate upon the boss, as shown, suitable openings, g, in the boss permitting the lubricating-material introduced between the tube and boss to pass through the latter, and thus to lubricate also the bearing-surfaces between the boss and the whirl and cup.

Figures 4 and 5 show, full size, the construction and method of applying whorles or whirls to be used instead of fliers.

P is the said whorle or whirl, and

Q, the rail in which it is suspended, and in which it is rotating, the hole in the whorl being of suitable diameter to allow the spool, when full of yarn, to pass

through it, the tweezles *p* carrying the yarn around the bobbins in the same manner as fliers do.

What I claim as my invention, and desire to secure by Letters Patent, is—

1. Two sets of spindles or bobbin-studs, F and H, arranged, respectively, upon parallel shafts, geared together and actuated substantially as described, so that, while one set is in position for spinning, the other set is in position for doffing.

2. The combination of the fliers C, suspended by their necks, and constructed substantially as set forth, with the means for lubricating the same, substantially as shown and described.

JOHN SPEIGHT.
